(57) CLAIM

The ornamental design for an athletic shoe tongue sleeve, as shown and described.

DESCRIPTION

FIG. 1 is a front view of an athletic shoe tongue sleeve showing my new design;

FIG. 2 is a back view thereof;

FIG. 3 is a top view thereof;

FIG. 4 is a bottom view thereof;

FIG. 5 is a right side view thereof;

FIG. 6 is a left side view thereof; and,

FIG. 7 is a perspective view thereof.

The dashed-dot-dashed lines represent stitching and the even dashed broken lines of an opening represent unclaimed environment that forms no part of the claimed design.
